UNITED STATES PATENT OFFICE.

MORTON C. TALCOTT, OF EAST HARTFORD, CONNECTICUT, ASSIGNOR TO THE BILLINGS & SPENCER COMPANY, OF HARTFORD, CONNECTICUT, A CORPORATION OF CONNECTICUT.

DROP HAMMER.

Application filed August 30, 1923. Serial No. 660,137.

This invention relates to drop hammers of the sort having a hammer adapted for vertical reciprocating movement, a board connected to the hammer, a plurality of lifting rolls spaced longitudinally of the board and arranged to grip the same, and means for moving the rolls into gripping engagement with the board to raise the same and the hammer. A drop hammer of this type 5 is disclosed and claimed in the co-pending application of Raymond S. Clark, George C. Prime and Morton C. Talcott, Serial No. 523,606, filed December 20, 1921, now Patent No. 1,670,493, patented May 22, 1928.

10 The aim of the present invention is to provide in a drop hammer of this type various features of advantage and, more particularly, to provide a very simple, strong, and mechanically effective connection between the friction bar or actuating means and the rolls so that they are operated in such manner as to properly grip the board.

15 Other objects of the invention will be in part obvious and in part pointed out hereinafter.

Figure 1 is a side elevation, with parts in section, of so much of a drop hammer as is necessary to illustrate my invention; and

20 Fig. 2 is a front view, with parts in section, of the roll operating mechanism.

25 Referring to the drawings in detail, 10 is a board adapted to be attached to a hammer (not shown) and adapted to be raised by a plurality of rolls spaced along the board and mounted in a head 11 supported on the uprights 12 between which the hammer reciprocates. There is shown, in the accompanying drawings, two sets or pairs of rolls, the rolls of one set being indicated by the numeral 13 and those of the other set by the numeral 14. The rolls of each set are continuously rotated in opposite directions in any suitable manner, in the present instance only the driving pulleys 15 being 30 illustrated, as the specific manner in which the rolls are driven forms no part of the present invention.

35 The rolls are mounted for movement or adjustment towards and away from the board. In the present illustrative disclosure, each of the rolls is keyed to a respective shaft 17, and the opposite ends of these shafts are journaled in eccentrics 18 mounted for rotation in bearings 19 provided in the sides of the head 11. The ecc-

40 centrics for each shaft are connected by yokes 20. If desired, the construction may be such that both rolls of each set move in unison towards and away from each other to grip and release the board. In the present instance, however, the front rolls only are adapted to be moved into and out of engagement with the board. The eccentric yokes 20 for the back rolls are arranged to move the rolls toward and from the board 45 for adjustment only, so as to regulate the position of these rolls relative to the board. To this end, the back or rear yokes may be connected by a link 43, and, connected to one of the yokes, may be a rod 44, the lower 50 end of which is adjustably connected to the frame upright 12, as indicated by the numeral 45.

55 The forward yokes are connected together by a link mechanism which, in turn, is connected to a source of board-gripping pressure constituted in the present case by a friction bar, and this link mechanism is such that the front rolls are moved substantially in unison into and out of engagement with 60 the board, and these rolls may independently accommodate themselves to the board during the lifting operation. In the present illustrative disclosure, this link mechanism includes one or more links 22 (in the present 65 instance two such links being shown) and toggle links 23 and 24. The upper ends of the links 22 are pivotally connected to the upper yoke by means of a pivot member or pin 25 carried by lugs 26 extending from the 70 forward face of the upper yoke. The opposite or lower ends of the links 22 are connected to the lower yoke by means of oblong slots 33 and a pin 27 carried by suitable lugs 75 28 on this yoke providing a certain limited amount of lost motion later referred to. The toggle link 24, at its lower end, is journalled on the pin 27, and the adjacent ends of the toggle links are connected together by 80 a pivot pin or bolt 29. In the present instance, the friction bar, designated by the 85 numeral 30, is directly connected to the pivotal connection between the toggle links; for instance, the upper end of the friction bar may have a yoke 31 straddling the adjacent 90 ends of the toggle links 23 and 24 and, pivotally connected thereto by the pivot member 95 29.

100 The operation of the machine is briefly as follows. When the hammer approaches the 110

end of its upward stroke, it raises the friction bar 30, thus causing the same, through the links 22 and the toggle links 23 and 24, to swing the front eccentric yokes in a clockwise direction, resulting in the front rolls 13 and 14 being withdrawn from the board 10. The friction bar is now held in raised position by means of suitable knock-off mechanism (not shown) until the hammer 10 again descends. When the hammer descends and reaches the end of its downward stroke, the knock-off mechanism is tripped, whereupon the friction bar will fall and its weight will cause the front eccentric yokes to be rotated in a counter-clockwise direction, thereby bringing the front rolls into engagement with the board, resulting in the board and hammer being lifted. The pressure, due to the weight of the falling friction bar, is transmitted positively to each yoke or roll support 18, so that both rolls are positively advanced to and against the board as distinguished from the yielding or non-positive action of one of the rolls in the prior application above referred to, and at the same time, the two rolls are capable of free, self-adjustment or compensating movement with respect to each other and the friction bar, which is to say, that the pressure of the friction bar is equally divided as between the two rolls and both of them thus obtain an equal friction grip on the board on all occasions. This division and equalization of the pressure enables the degree of pressure 35 of the rolls on the board to be set in the first instance so that both obtain an adequate friction with little or no slippage and with minimum danger or over-compression of the board which, as well-known, greatly shortens 40 its useful life.

The weight of the friction bar is exerted as compressive and tensile forces respectively on the lower and upper toggle links and for all angular variation of said links 45 occurring in normal practice, the resulting division of the force applied is exactly equal. Such angular change of the linkage is so slight that the horizontal component of the resulting movement of the pivot pin 29 is 50 practically negligible; its actual motion is mainly vertical and no special provision or joint is therefore necessary between such pin and the friction bar, although such a joint may be provided if desired. It will, of course, be understood that the centers of the pivot pins 25 and 27 are equi-distant from the centers of the journals of their respective roll supports or eccentrics 18 and that the 55 eccentricities of said supports are exactly equal and in the same direction; if otherwise, the linkage angle would be required to be modified accordingly and as will be apparent, in order to keep the division equal.

On the upstroke of the friction bar, the 60 pressure of both rolls on the board is in-

stantly relieved and, in order that both rolls shall then be positively withdrawn from the board, the throw-off links 22 are provided. The oblong slots 33 in the lower ends of these links are made long enough so that the 70 links do not affect or interfere with the equal division of the applied force but are nevertheless available for compelling conjoint movement of both roll supports as soon as the slight amount of lost motion represented by the slots has been taken up. This is a feature of the present invention which can be applied with great advantage to any system of pressure-equalizing mechanism in which the pressure is imparted 75 positively or non-yieldingly to both or all the movable roll supports; its advantage is that it effectually avoids the polishing of the board by the roll or rolls and the consequent impairment of the friction surface which 80 would otherwise occur when the board is in its lowest position. The spot where such polishing might occur on such occasions is the spot where it is most important that the friction co-efficient be as high as possible, 85 because this is the place where the roll performs its maximum work, the work of starting the hammer upwards from rest. It will be apparent to those skilled in this art, and as above stated, that this advantage applies 90 to any equalizing positive-action pressure system of roll control and that the necessary modification in form of the throw-off mechanism for accommodating different types of 95 such systems can be readily made. 100

The connection together of the roll supports or yokes of the two back rolls, as above described, also constitutes part of this invention inasmuch as it is by virtue of the self-accommodation of the front roll supports 105 under the positive action pressure system above described, that it becomes practical to impart equal adjustment to both back rolls and accordingly there is no intended limitation in this invention to the use of 110 said joint back roll adjustment with any particular type of pressure distributing system. It will be understood that the back roll adjustment is for taking up wear.

It should be explained finally that while 115 a gravity friction bar, as herein shown, is a simple and commonly used source of board-gripping pressure, and is preferred in the present case, the principles above described and hereinafter identified by the 120 claims are not dependent on the use of such a bar. When such a bar is employed, its own weight plus the weight of its attached parts and linkage is made heavy enough to overcome the friction acting on both roll 125 supports and for this purpose may be no heavier than needed for moving a single roll if the radii of the centers of the pivot pins 25 and 27 are of appropriate length.

Thus, by the above construction, are ac- 130

complished, among others, the objects hereinbefore referred to.

As many changes could be made in the above construction and many apparently 5 widely different embodiments of this invention could be made without departing from the scope thereof, it is intended that all matter contained in the above description or shown in the accompanying drawing shall 10 be interpreted as illustrative and not in a limiting sense.

I claim as my invention:

1. In a board drop hammer, upper and lower lifting rolls, a gravity friction bar, 15 and a positive-action pressure-equalizing connection between said bar and said rolls.

2. In a board drop hammer upper and lower lifting rolls, a source of board-gripping pressure therefor, positive-action pressure-equalizing connection between said source and rolls and means for compelling 20 positive withdrawal of both rolls from the board.

3. In a board drop hammer the combination of upper and lower pairs of lifting 25 rolls, a source of board-gripping pressure therefor, a positive-action equalizing connection between said source and one roll of each pair and a single means for adjusting 30 the working positions of both the other rolls of said pairs.

4. In a board drop hammer, the combination of a plurality of lifting rolls spaced longitudinally of the board, individual roll 35 supports therefor, a source of board-gripping pressure and a positive-action pressure-equalizing connection between said source and said roll supports.

5. In a board drop hammer, the combination of a plurality of lifting rolls spaced 40 longitudinally of the board, independent roll supports therefor, a source of board-gripping pressure, and a positive-action pressure-equalizing connection between said source and roll supports, said connection including angularly related links respectively 45 pivoted to said supports and to a common actuating member.

6. In a board drop hammer, the combination of lifting rolls spaced longitudinally 50 of the board, a pressure source, and a positive-action pressure-equalizing connection between the same and said supports, said connection including angularly related links, 55 the pivotal axes whereof are parallel with the roll axes.

7. In a board drop hammer, the combination of lifting rolls spaced longitudinally 60 of the board, independent roll supports therefor, a friction bar, and a positive-action pressure-equalizing connection between said bar and both said roll supports.

8. In a board drop hammer, the combination of lifting rolls spaced longitudinally 65 of the board and journalled in independent

roll supports, a source of board-gripping pressure, a positive-action pressure-equalizing connection between said source and said supports and a positive throw-off means included in, or associated with, said connection. 70

9. In a board drop hammer, the combination of lifting rolls spaced longitudinally of the board and journalled in independent roll supports, a source of board-gripping pressure, a positive-action pressure-equalizing connection between said source and said supports and a positive lost motion connector means between said roll supports adapted to 75 compel conjoint withdrawal of said rolls 80 from the board.

10. In a drop hammer, a frame, a hammer suitably guided therein, a board connected to the hammer, a plurality of lifting rolls spaced apart longitudinally of the board, 85 eccentrics for moving said rolls relative to said board, yokes connecting the eccentrics for each roll, an actuating member connected to the respective yokes, and a link connecting said yokes, said link having a slot and pin connection with one of said yokes whereby the yokes have a slight relative motion. 90

11. In a drop hammer, a frame, a hammer suitably guided therein, a board connected to said hammer, a plurality of lifting rolls 95 spaced apart longitudinally of the board, eccentrics for moving the rolls relative to the board, a yoke connecting the eccentrics for each roll, an actuating member, a link between said member and each of said yokes, and a connecting link between said yokes and permitting a slight relative motion therebetween. 100

12. In a drop hammer, a frame, a hammer suitably guided therein, a board connected to said hammer, a plurality of lifting rolls spaced apart longitudinally of said board, eccentrics to move said rolls into engagement with the board, yokes connecting the eccentrics of each roll, a pair of toggle links pivoted at their free ends to the respective yokes, a friction bar directly pivoted to both said toggle links at their adjacent ends and a link between said yokes and having a slight lost motion relative to one of them. 110

13. In a board drop hammer the combination of upper and lower pairs of lifting rolls journalled in independent roll supports, a source of board-gripping pressure, a pressure-equalizing connection between said source and the roll support of one roll of each pair and a single means for simultaneously adjusting the working position of the other rolls of said pairs. 120

14. In a board drop hammer, upper and lower pairs of lifting rolls, a source of board-gripping pressure, a pressure-equalizing connection between said source and one roll of each pair, an eccentric support for the other 125 130

rolls of each pair and means for simultaneously angularly adjusting said eccentrics.

15. In a board drop hammer, pairs of lifting rolls spaced longitudinally of the board, a source of board-gripping pressure therefor, a positive-action pressure-equalizing connection between said source and one

roll of each pair, said connection being provided with means for compelling positive conjoint withdrawal of said rolls, and means 10 for simultaneously changing the working positions of the other rolls of said pairs.

MORTON C. TALCOTT.
